Patented Apr. 26, 1927.

1,626,522

UNITED STATES PATENT OFFICE.

STANLEY B. FREIBERG, OF CINCINNATI, OHIO.

COLOR PRINTING.

No Drawing.

Application filed January 9, 1926. Serial No. 80,359.

My invention relates to printing in colors, and particularly to offset work, in which the plate itself does not directly contact with the object being printed.

5 In printing in colors, the effect gained is considered most perfect when the colors are clear, and to appearance laid on as paint, instead of being printed in ink.

However, it is bad to give the impression 10 of a decalcomania or embossed effect, as this does not appear natural. Offset printing is capable of producing the softest and most nearly hand colored effects, and hence the application of my invention to offset printing 15 is, I consider, its most important phase, since it imparts a freshness and brilliance, which offset normally lacks.

Referring very briefly to offset printing with etched plates, it will be noted that there 20 are plates formed of the artist's production, which is first photographed, through color filters to produce a plate for each color of the production. These plates are used to print on the blankets, and the blankets print 25 upon the cardboard, paper or whatever is being printed, in the colors for which the plates were formed.

By my invention, after the object is fully 30 printed, an additional printing is made with a suitable varnish or size, such as copal varnish, with sufficient lubricant to render it less tacky, using a plate prepared for this purpose. Also the varnish imprint can be made at other stages, and additional colors 35 printed over it.

Either a master plate is formed with desired parts of the original design etched 40 therein, or a plate is used which is the same as one used for any one of the printed colors of the design.

For example in gift cards, I may employ 45 a light color such as buff or cream for the first plate, which prints those parts of the design that are a light color, and over which are printed subsequent blacks, blues, greens, light pinks, etc., to gain desired color effects, each imprint for each color being brought 50 into registry with the previous imprints. Finally after the sheet of cards is finished, I take the same plate that has printed one 55 of the colors and use it with a copal varnish instead of an ink. The plate which printed the light blue is usually the most effective, but I use the plate for that color which will give the most brilliant effect for the type of offset I am producing.

The result of use of my process, whether all or only a part of the design is given a superimposed coating of the varnish, is to brighten the colors, and give the object a 60 hand touched effect, which falls well short of any raised effect, but gives a more pleasing appearance to the eye.

The use of my process in offset printing is particularly valuable as the amount of 65 color used and the kind of object printed lends itself well to hand work effect, and the amount of the varnish applied will be enough to brighten the colors, heighten the 70 clearance of the design, and yet will not be apparent as a gloss unless the observer slants the object to the light to obtain a reflection. Furthermore, this gloss, such as it is, gives the effect of thickness without artificiality, which heightens the beauty of the design. 75 More than one varnish imprint may be used, with a master plate, or any or all of the original plates, and at any stage of the printing although at the close is preferred.

There is one other kind of printing in 80 which my invention has excellent application and that is in lithography. In lithography I may provide an extra stone for printing the varnish or size impression, or use any one of the stones over again for 85 making the transparent imprint. The hand painted effect of the best type of lithography is considerably enhanced by my process.

Having thus described my invention, what 90 I claim as new and desire to secure by Letters Patent, is:—

1. A process of color printing, which consists in applying successive imprints in register for each color, among which imprints 95 is one employing a transparent varnish or size also in register.

2. A process of color printing, which consists in applying colors by successive imprints in register and then imprinting over 100 the completed design a transparent varnish or size imprint also in register.

3. A process of color printing by offset, which consists in applying successive imprints in register for each color, among 105 which imprints is one employing a transparent varnish or size also in register.

4. A process of color printing by offset, which consists in applying colors by successive imprints in register and then imprinting over the completed design a transparent 110 varnish or size imprint also in register.

5. A process of color printing by offset, which consists in applying successive imprints in register for each color, among which imprints is one employing a transparent copal varnish also in register.
6. A process of offset color printing which consists in applying colors by successive im-
- prints in register, and then imprinting over the completed design a transparent varnish or size by use of a plate which is the same 10 plate or a replica of any one of the plates used in the offset printing.

STANLEY B. FREIBERG.
